LEWIS D. CHRISTIE, OF BRIDGEPORT, CONNECTICUT, ASSIGNOR TO THE UNION METALLIC CARTRIDGE COMPANY, OF BRIDGEPORT, CONNECTICUT, A CORPORATION OF CONNECTICUT.

SCATTER-LOAD FOR SHOT-SHELLS.

No. 873,347.

Specification of Letters Patent.

Patented Dec. 10, 1907.

Application filed June 10, 1907. Serial No. 378,075.

To all whom it may concern:

Be it known that I, LEWIS D. CHRISTIE, a citizen of the United States, residing at Bridgeport, county of Fairfield, State of Connecticut, have invented a new and useful Scatter-Load for Shot-Shells, of which the following is a specification.

This invention relates to the type of short range cartridges in which the scattering of the shot, when fired from a gun, is effected by dividing the shot charge into sections separated by wads, and the invention has for its object to provide scatter loads for shot cartridges which shall be complete in themselves and adapted to be made and sold independently of the shells in which they are used.

With this and other objects in view I have devised the novel scatter load for shot shells of which the following description in connection with the accompanying drawing is a specification, reference characters being used to indicate the several parts:

Figures 1 and 3 are views partly in elevation and partly in section illustrating slight variations in the mode of making my novel scatter load; Fig. 2 is a plan view corresponding with Fig. 1; and Fig. 4 is a plan view corresponding with Fig. 3.

The essential features of my novel scatter load are that the shot comprising the load are divided into sections indicated by 10, the sections are separated by wads indicated by 11, wads being likewise placed at the bottom and top and the load as a whole is inclosed in a layer of paper sufficiently strong to permit the load to be handled conveniently, but offering slight resistance when fired from a gun and permitting scattering of the shot.

The thickness of the outer wrapping of paper which is indicated by 12 is greatly exaggerated in the drawing.

In Fig. 1 I have illustrated a scatter load comprising four sections of shot with top and bottom wads and three intermediate wads and a wrapping 12 secured in place by past-

ing it to the top and bottom wads, as at 14 (Figs. 1 and 2).

In Figs. 3 and 4 I have illustrated a scatter load comprising three sections of shot with top and bottom wads and two intermediate wads. In this form I have shown the outer wrapping 12 as made longer than the charge and as secured in place by simply crimping it over the top and bottom wads, as at 13, 55 without pasting. In practice these loads are made in an assembling machine. If the top and bottom wads are to be retained in place by pasting the wrapping thereto, paste is applied to the edges of these wads 60 before they are placed in the wrapping. If the wrapping is secured in place by crimping over the top and bottom wads, the crimping is, of course, performed after the last section of the charge is placed in the wrapping. It 65 should be understood, however, that the method of making my novel scatter loads is wholly unimportant so far as the present invention is concerned.

Having thus described my invention, I claim:

1. A scatter load for shot cartridges comprising a shot charge divided into a plurality of sections separated by wads, top and bottom wads and a covering of light paper inclosing the charge and secured in place independently of the cartridge shell.

2. A scatter load of shot cartridges comprising a shot charge divided into a plurality of sections separated by wads, top and bottom wads and a covering of light paper inclosing the charge and crimped above and below the top and bottom wads, respectively, the said load being capable of handling independently of the cartridge shell.

In testimony whereof I affix my signature, in presence of two witnesses.

LEWIS D. CHRISTIE.
